WINDOW SHADE DISPLAY CASE

Donald A. Fletcher, 109 Shabbona Drive, Park Forest,
Ill., Roger R. Ringger, 22013 Millard, Richton Park,
Ill., and Shepard Whitman, 2834 W. Berwyn, Chicago,
Ill.

Filed May 18, 1964, Ser. No. 80,007

Term of patent 14 years

(Cl. D80—9)

Fig. 1

Fig. 2

Fig. 5

Fig. 4

We claim:

The ornamental design for a window shade display case, as shown and described.
